[57]

A toilet stool and air deodorizer structure is positioned adjacent a toilet stool and operative to move air and odors from the toilet stool and direct same through an air filter and away from the toilet stool. The air mover and deodorizer includes a motor driven fan positioned with the motor being energized by weight on the toilet seat depressing same to complete an electrical circuit to said motor. The fan is in a housing and operative to draw air through an inlet positioned between a toilet seat and a toilet bowl rim and move the air outwardly through the air deodorizing filter.

TOILET STOOL AIR DEODORIZER STRUCTURE

The present invention relates to air deodorizers and more particularly to an economical, safe air deodorizer structure for use with a toilet stool to deodorize air therefrom.

The principal objects of the present invention are: to provide an air deodorizer structure particularly adapted to remove odors and freshen air adjacent toilet stools and direct freshened air away from the toilet stool; to provide such structure which is easy to disassemble, clean, and reassemble; to provide such a structure having an inlet adapted to be positioned between a toilet seat and a toilet bowl rim and which may be reversed on a housing of the air deodorizer structure whereby same may be used on either side of a toilet stool; to provide such a structure that is adjustable to accommodate different height stools; to provide such an air deodorizer structure having resilient means adapted to effect a selected spacing of the toilet seat above the toilet bowl rim to permit the inlet to be received therebetween; to provide such an air deodorizer structure which is automatic in operation and is activated by weight on the toilet seat depressing same and closing a switch in an electric circuit to the fan motor; to provide such a structure in which all electrical components are enclosed and spaced from a user of the toilet; to provide such a structure which is removably positioned alongside a stool and is free of any fastening tie thereto; to provide such a structure which is attractive in appearance and which may be provided in colors to coordinate with the color scheme in a bathroom; and to provide such a toilet stool air deodorizer which is economical to manufacture, durable in construction, positive in operation, and particularly well adapted for the proposed use.

Other objects and advantages of this invention will become apparent from the following description taken in connection with the accompanying drawings wherein are set forth, by way of illustration and example, certain embodiments of this invention.

The drawings constitute a part of this specification and include an exemplary embodiment of the present invention and illustrate various objects and features of the toilet stool air deodorizer.

FIG. 1 is a perspective view of a toilet stool and an air deodorizer structure embodying features of the present invention and shown in position for use.

FIG. 2 is an enlarged perspective view of the toilet stool air deodorizer structure.

FIG. 3 is an enlarged plan view of the air deodorizer structure.

FIG. 4 is an enlarged side elevational view of the air deodorizer structure.

FIG. 5 is a further enlarged transverse sectional view taken on line 5-5, FIG. 4.

FIG. 6 is a longitudinal sectional view at the same scale as FIG. 5 and taken on line 6-6, FIG. 3.

Referring more in detail to the drawings:

As required, detailed embodiments of the present invention are disclosed herein. However, it is to be understood that the disclosed embodiments are merely exemplary of the invention which may be embodied in various forms. Therefore, specific structural and functional details disclosed herein are not to be interpreted as limiting but merely as a basis for the claims and as a representative basis for teaching one skilled in the art

to variously employ the present invention in virtually any appropriately detailed structure.

In the disclosed embodiment of the present invention, the reference numeral 1 generally designates a toilet stool air deodorizer structure adapted to be positioned adjacent a toilet stool 2 and operative to move air from the toilet stool 2 and direct same through an air deodorizing filter 3 and away from the toilet stool 2. The air mover and deodorizer structure 1 includes a fan 4 positioned in a housing 5 and operative to draw air inwardly through an inlet 6 communicating with the housing 5 and positioned between a toilet seat 7 and a toilet bowl rim 8 and move the air and odors outwardly through the air deodorizing filter 3 in response to weight applied to the toilet seat 7, such as a person sitting on the toilet seat 7, which completes an electrical circuit to the fan 4.

The housing 5 preferably is of a structure that is easily cleaned and of electrical non-conductive material with the walls defining passages and chambers for flow of air and odors therethrough. In the illustrated structure, the housing 5 has a base portion 9 with an air outlet therein and an upstanding portion 10 extending upwardly from the base portion 9. The illustrated base portion 9 has top and bottom walls 11 and 12 respectively and opposed side walls 13 and 14 extending between the top and bottom walls 11 and 12. The base portion 9 includes opposed end walls 15 and 16 with one of the end walls, for example the end wall 15, having an air outlet therein adapted to have the air deodorizing filter 3 mounted therein.

The base portion 9 includes an intermediate wall or partition 17 positioned between the end walls 15 and 16 and having an aperture or passage 18 therethrough and adapted to have the fan 4 positioned in the aperture or passage 18.

The upstanding portion 10 of the housing 5 is illustrated as including an upwardly tapered section 19 positioned at and extending upwardly from one end of the base portion 9. The upwardly tapered section 19 is formed by generally upwardly inclined side walls 20 and 21 converging upwardly and inwardly from the sidewalls 13 and 14 respectively of the base portion 9. The upwardly tapered section 19 includes opposed end walls with one of the end walls being coplanar with and extending upwardly from the other end wall 16 of the base portion 9 and a second end wall 22 which is preferably aligned with and extends upwardly from the partition 17 of the base portion 9.

The upstanding portion 10 includes an upper portion 23 extending upwardly from the tapered section 19 and may be of any suitable non-round shape adapted to maintain the inlet 6 in any desire orientation. In the illustrated structure, the upper portion 23 is a generally tubular member of rectangular shape having extensions of the end walls 16 and 22 defining the ends of the upper portion 23 and side walls 24 and 25 extending upwardly from the side walls 20 and 21 respectively of the tapered section 19.

The air mover and deodorizer structure 1 includes adjustable means on and communicating with the upper portion 23 of the housing 5 for defining the inlet 6 which is adapted to be positioned between a toilet bowl rim 8 and a toilet seat 7 for directing flow of air into the housing 5. In the illustrated structure, a tubular nozzle member 26 which is easily cleaned and of electrically non-conductive material and which has a first

portion 27 sleeved on the upper portion 23 of the upstanding portion 10 of the housing 5 and a second or outstanding portion 28 extending outwardly from the first portion 23 and having the inlet 6 therein. In the illustrated structure, the first portion 27 is tubular and also has a non-round shape corresponding to the shape of the upper end portion 23 of the upstanding portion 10. The first portion 27 is illustrated as being generally rectangular in shape and is movable vertically along the upper portion 23 thereby permitting adjustment of the position of the inlet 6 relative to the toilet bowl rim 8.

The outstanding portion 28 of the nozzle member 26 having the inlet 6 therein is illustrated as also being generally rectangular in cross-section and tubular to provide communication with the first portion 27 and with the interior of the housing 5. The illustrated second or outstanding portion 28 of the nozzle member 26 has top and bottom walls 29 and 30 respectively and opposed side walls 31 and 32 extending between side edges of the top and bottom walls 29 and 30. The top and bottom walls 29 and 30 have peripheral edges which define an arcuate path corresponding to the general shape of the toilet bowl rim 8.

The second or outstanding portion 28 of the nozzle member 26 has wall means intermediate the ends thereof and intermediate the side walls 31 and 32 defining a guide recess or socket 33, for a purpose later described. In the illustrated structure, the socket 33 has the upper or interior surface of the bottom wall 30 defining the lower end thereof.

The housing 5 includes a removable linkage cover 34 mounted on the nozzle member 26 and in alignment with the upper portion 23 of the upstanding portion 10 of the housing 5. The linkage cover 34 encloses a portion of a linkage, as later described, to move a switch element to complete a circuit to the fan 4 and includes a top wall 35 spaced upwardly from the top wall 29 of the outstanding portion 28 of the nozzle member 26. The linkage cover 34 includes laterally spaced side walls 36 and 37 preferably positioned above and aligned with the side walls 24 and 25 respectively of the upper portion 23. The side walls 36 and 37 depend from the top wall 35 and preferably have lower edges thereof in supported engagement with the top wall 29 of the nozzle member 26. The side walls 36 and 37 have means defining opposed guide way or slots, for a purpose later described.

The linkage cover 34 is preferably removably attached to the nozzle member 26 and in the illustrated structure, end support walls 38 and 39 are suitably removably attached to the side walls 31 and 32 of the outstanding portion 28 of the nozzle member 26, as by suitable screws 40.

The linkage cover 34 includes an extension at one end thereof and the extension has means for guiding a switch linkage, as later described, during movement thereof in response to weight being applied to the toilet seat, such as a person sitting on the toilet seat 7, to move respective components to complete an electrical circuit to the fan 4 thereby energizing same. In the illustrated structure, the extension includes an end wall 41 spaced outwardly from one of the end support walls and the end wall 41 is positioned above the top wall 11 of the base portion 9 of the housing 5 and has a suitable guide slot or way therein, for a purpose later described.

The toilet stool air mover and deodorizer structure 1 has a handle 42 removably mounted on the base por-

tion 9 whereby the air deodorizer 1 is portable. The handle is particularly constructed to be easily cleaned and is also of non-conductive material. The illustrated handle 42 includes a gripping portion 43 and a base portion 44 which is hollow to receive suitable electrical conductors and suitable means for removably securing the handle 42 to the base portion 9 of the housing 5. In the illustrated embodiment, a suitable fastening member, such as a screw 45, extends upwardly through the top wall 11 of the base portion 9 and is suitably received in a suitable threaded socket in the base portion 44 of the handle 42.

The handle 42 includes spaced walls to define a switch chamber containing electrical terminals and a contact member, as later described, and having means for guiding the contact member into engagement with the electrical terminals. In the illustrated embodiment, the switch chamber is defined by a top wall 46 having an aperture or slot therein, for a purpose later described, and side walls 47 and 48 depending from the top wall 46 and being in engagement with the end wall 22 of the tapered section 19 and with the top wall 11 of the base portion 9 thereby closing the switch chamber which includes an end wall 49 spaced from the end wall 22 of the upstanding portion 10. A partition 50 having a vertically extending slot therein is positioned between the end wall 49 of the handle 42 and the end wall 22 of the upstanding portion 10 of the housing 5, for a purpose later described.

The air deodorizing filter 3 is mounted on the base portion 9 of the housing 5 and is operative to freshen air and odors flowing outwardly through the outlet in the base portion 9. The air deodorizing filter 3 is suitably supported on the base portion 9, as by being mounted in a frame 51 removably attached to the end wall 15 of the housing 5, as by a plurality of spaced screws 52. The filter media may be any suitable material adapted to absorb odors from air passing therethrough, such as activated charcoal or the like.

The fan 4 may be any suitable unit having air moving blades 53 positioned in the aperture or passage 18 through the partition 17 in the base portion 9 of the housing 5. The air moving blades 53 are adapted to effect flow of air and odors inwardly through the inlet 6 and outwardly through the air outlet and air deodorizing filter 3 mounted on the housing 5. The fan 4 includes a suitable electric motor 54 which is operatively connected to the air moving blades 53 and suitably supported within the base portion of the housing 5, as by legs 55 and 56 suitably secured to the bottom wall 12 of the housing 5.

The air mover and deodorizer structure 1 includes switch means electrically connected to the motor 54 of the fan 4 and operative to energize the motor 54 in response to weight being applied to the toilet seat 7, such as a person sitting on the toilet seat 7. The illustrated switch includes first and second spaced electrical terminals 57 and 58 positioned in the switch chamber of the handle 42 and extending between and supported on the end wall 49 and the partition 50 of the handle 42. The electrical terminals 57 and 58 are electrically connected to a suitable source of power, such as house current, and to the electric motor 54 of the fan 4. An electrically conductive contact member 59 is also positioned between the end wall 49 and the partition 50. The contact member 59 is movable vertically in the slot in the partition 50 and is normally positioned out of

contact with the terminals 57 and 58 and is movable into engagement with the terminals 57 and 58 to complete an electrical circuit to the motor 54.

A guide member or block is positioned in the space between the end wall 49 and the partition 50 and has a guide way or passage therein to limit movement of the contact member 59 to a single plane. The guide way or passage in the guide member or block is the same size as the guide way or slot in the partition 50.

The air mover and deodorizer structure 1 includes a linkage adapted to move the contact member 59 generally vertically into engagement with the terminals 57 and 58 in response to weight on the toilet seat 7, such as a person sitting on a toilet seat 7. In the illustrated embodiment, an activating arm 60 is resiliently maintained in spaced relation with the top wall 29 of the second or outstanding portion 28 of the nozzle member 26. The activating arm 60 has a depending guide member 61 adapted to be received in the guide socket or recess 33 in the outstanding portion of the nozzle member 26.

The activating arm 60 is resiliently supported in spaced relation with the nozzle member 26 and in the illustrated structure, a suitable resilient member, such as a spring 62, is sleeved on the guide member 61 and has respective opposite ends thereof in engagement with the bottom wall of the guide socket 33 and the lower surface of the activating arm 60.

The activating arm 60 has a portion thereof received within the linkage cover 34 and has laterally extending projections 63 and 64 each adapted to engage one of the side walls of the linkage cover 34 to limit outwardly movement of the activating arm 60. The projections 63 and 64 and the guide member 61 cooperate to restrict longitudinal movement of the arm 60 laterally of the linkage cover 34 and the guide slots in the side walls 36 and 37 of the linkage cover 34 restrict lateral movement of the activating arm 60. The portion of the activating arm 60 positioned within the linkage cover 34 has an upwardly extending rib 65, for a purpose later described.

The linkage to move the contact member 59 includes a contact support member 66 having the contact member 59 suitably mounted thereon. The contact support member 66 extends vertically through the slot in the top wall 46 defining the switch chamber and is positioned adjacent the partition 50 of the handle 42 and the contact member 59 extends through the slot in the partition 50 and is received in the passage in the guide member or block.

The linkage to move the contact member includes means supported on the actuating arm 60 and attached to the contact support member 66 for moving the contact member 59 to complete the electrical circuit in response to weight being applied to the toilet seat 7, such as a person sitting on the toilet seat 7. In the illustrated embodiment, an upright member 67 is positioned in parallel spaced relation with the contact support member 66 and has suitable means securing the upright member 67 to the contact support member 66, such as a set screw 68 extending through the upright member 67 and into engagement with the contact support member 66 for moving same into clamped engagement with a body member 69 of a clamping device thereby effecting connection between the contact support member 66 and the upright member 67.

The upright member 67 has a slot or aperture in an upper end thereof adapted to receive a generally horizontal linkage member 70 whereby the upright member 67, the contact support member 66, and the contact member 59 are supported on the horizontal linkage member 70 which is supported on the activating arm 60. In the illustrated embodiment, the horizontal linkage member 70 has an upwardly extending notch 71 in a lower edge thereof adapted to receive the upwardly extending rib 65 of the activating member 60 therein. The generally horizontal linkage member 70 is illustrated as a planar member having a shoulder 72 adjacent an outer end thereof and adapted to be engaged by the upright member 67 to substantially limit movement of the upright member 67 along the horizontal member 70. The horizontal linkage member 70 has an end portion thereof extending through the guide slot in the end wall 41 of the extension of the linkage cover 34, thereby limiting lateral movement of the switch linkage.

The air deodorizer structure 1 is particularly adapted for use with a toilet stool 2 having an upper edge thereof defining the toilet bowl rim 8. The toilet stool 2 has a hinge member 73 for hingedly mounting the toilet seat 7 on the toilet stool 2. The toilet seat 7 is spaced from the toilet bowl rim 8 a selected distance to permit the activating arm 60 and the outstanding portion 28 of the nozzle member 26 to be positioned between the toilet seat 7 and the toilet bowl rim 8. In the illustrated embodiment, spacers 74 are positioned between the hinge member 73 and the toilet bowl rim 8 to effect the selected spacing therebetween.

Suitable means are mounted on the toilet seat 7 and engageable with the toilet bowl rim 8 for resiliently maintaining a selected spacing therebetween until weight is applied to the toilet seat 7, such as a person sits on the toilet seat 7, thereby moving same and the activating arm 60 toward the toilet bowl rim 8. In the illustrated embodiment, spacer members 75 are suitably secured to the toilet seat 7 and each spacer member 75 has a resiliently supported projection 76 extending therefrom and engageable with the toilet bowl rim 8.

When a person sits on the toilet seat 7, the weight of the person compresses the spring 62 supporting the activating arm 60 and the resilient members supporting the projections 76 thereby allowing the activating arm 60 to move toward the nozzle member 26 which in turn allows the contact member 59 to move by gravity into engagement with the electrical terminals 57 and 58 thereby energizing the motor 54 and operating the fan 4. The air moving blades 53 of the fan 4 effect inwardly directed flow of air and odors through the inlet 6 in the outstanding portion 28 of the nozzle member 26 and through the aperture or passage 18 in the partition 17 and then through the air deodorizing filter 3 and away from the toilet stool 2 and the air deodorizer structure 1. Upon release of weight from the seat 7, the spring 62 and the resilient members supporting the projections 76 raise the seat 7 and the contact member 59 to turn off the fan 4.

The nozzle member 26 may be reversed to permit the air moving and deodorizer structure 1 to be positioned on the opposite side of the toilet stool 2. The linkage cover 34 is removably mounted on the nozzle member 26 and must then be reversed on the nozzle member 26 to maintain the end wall 41 in position above the han-

dle 42 to thereby serve as a guide for the movement of the horizontal linkage member 70 during movement of the contact member 59 into and out of engagement with the electrical terminals 57 and 58.

It is to be understood that while I have illustrated and described one form of my invention, it is not to be limited to this specific form or arrangement of parts herein described and shown.

What I claim and desire to secure by Letters Patent is:

1. A deodorizer device for a toilet having a toilet bowl with an enlarged rim at the upper end thereof and a toilet seat hingedly mounted on said bowl and having limited movement toward said bowl and a predetermined minimum space between said seat and rim comprising:

- a. a housing having an air outlet and a fan means and a filter unit therein arranged for support from a floor along side a toilet, said housing having a reduced upstanding duct portion and permitting air flow through the duct portion, fan means and filter unit to said air outlet;
- b. an inlet member having a wide generally flat portion extending between a toilet bowl rim and seat and having an inlet opening facing said bowl, said inlet member having a depending tubular duct telescopingly and adjustably engaged with said upstanding duct portion for adjusting the height of said flat portion to accommodate the height of said toilet with said upstanding duct portion;
- c. resilient means engaging said toilet seat and operative to swing same upwardly to a selected spacing from the bowl rim when in unloaded condition and permit the seat to be depressed to its minimum spacing when weight is applied thereto;
- d. switch means in the housing and having electrically conductive components with one being movable and operative to make and break an electric circuit to said fan means;
- e. actuating means on the inlet member and having a movable arm extending under the toilet seat for operation thereby in response to up and down movement of said seat;
- f. means including a link connecting the actuating means to the movable switch component to move same and make the electric circuit to the fan means when the seat is depressed, and to break said circuit when the seat is raised, said link including means for adjusting its length to accommodate the height adjustment of the inlet member.

2. A deodorizer device as set forth in claim 1 wherein:

- a. said actuating means includes a lever movably mounted on the inlet member;
- b. resilient means supported on said inlet member engages said arm and urges same upwardly lifting the lever and link to move the movable switch component to circuit breaking position when the toilet seat is in unloaded condition.

3. A deodorizer device as set forth in claim 1 wherein:

- a. said housing, inlet member, actuating means and link being of electrically non-conductive material;
- b. said electrically conductive components of the switch means include a pair of electrical terminals electrically connected to a source of power and to said fan means and said movable electrically con-

ductive component is a contact member movable into engagement with said terminals to complete an electrical circuit to said fan means;

c. said electrical terminals and said contact member are enclosed in the housing and the contact member is mounted on an end portion of said link with the link extending from the housing to said actuating means.

4. A deodorizer device for a toilet having a toilet bowl with an enlarged rim at the upper end thereof and a toilet seat hingedly mounted on said bowl and having limited movement toward said bowl and a predetermined minimum space between said seat and rim comprising:

- a. a housing having an air outlet and a fan means and a filter unit therein arranged for support from a floor along side a toilet, said housing having a reduced upstanding duct portion and permitting air flow through the duct portion, fan means and filter unit to said air outlet;
- b. an inlet member having a tubular nozzle member having a wide generally flat portion extending between a toilet bowl rim and seat and having an inlet opening facing said bowl, said inlet member having a depending tubular duct telescopingly and adjustably engaged with said upstanding duct portion for adjusting the height of said flat portion to accommodate the height of said toilet with said upstanding duct portion;
- c. an actuator housing on said inlet member along side of said toilet seat, and having an opening facing said seat;
- d. resilient means engaging said toilet seat and operative to swing same upwardly to a selected spacing from the bowl rim when in unloaded condition and permit the seat to be depressed to its minimum spacing when weight is applied thereto;
- e. switch means in the housing and having electrical terminals electrically connected to a source of power and said fan means and a movable contact movable into and out of engagement with said terminals to make and break an electric circuit to said fan means;
- f. a lever in the actuation housing movably mounted on the inlet member;
- g. an arm engaged with said lever and having a portion extending through the actuator housing opening above said tubular nozzle and under the toilet seat for operation thereby in response to up and down movement of said seat;
- h. means including a link connecting the lever to the movable contact to move same and make the electric circuit to the fan means when the seat is depressed, and to break said circuit when the seat is raised;
- i. means on said inlet member resiliently urging said arm portion upwardly to lift the lever and link to move the movable contact to circuit breaking position when the toilet seat is in unloaded condition.

5. A deodorizer device as set forth in claim 4 wherein:

- a. said housing, inlet member, lever, arm and link being of electrically non-conductive material;
- b. said electrical terminals and said contact member are enclosed in the housing and the contact member is mounted on an end portion of said link with the link extending from the housing to said lever.
